UNITED STATES PATENT OFFICE

167,924

CANDELABRUM

Victor H. Bisharat, Berkeley, Calif.

Application July 10, 1951, Serial No. 15,812

Term of patent 7 years

(Cl. D48—2)

To all whom it may concern:

Be it known that I, Victor H. Bisharat, a citizen of the United States of America, residing in Berkeley, in the county of Alameda and State of California, have invented a new, original, and ornamental Design for a Candelabrum, of which the following is a specification, reference being had to the accompanying drawing, forming part thereof:

In the drawing:

Figure 1 is a perspective view of a candelabrum showing my new design;

Figure 2 is a perspective view thereof taken from the right of Figure 1; and

Figure 3 is a top plan view thereof.

I claim:

The ornamental design for a candelabrum, as shown.

VICTOR H. BISHARAT.
